US00D537159S

(12) **United States Design Patent** (10) **Patent No.:** **US D537,159 S**
(45) **Date of Patent:** **** Feb. 20, 2007**

(54) **RANGE HOOD**

(75) Inventor: **Keiichi Kashimura**, Kanagawa-ken (JP)

(73) Assignee: **Fuji Industrial Co., Ltd.**, Sagamihara (JP)

(**) Term: **14 Years**

(21) Appl. No.: **29/226,617**

(22) Filed: **Mar. 31, 2005**

(51) **LOC (8) Cl.** **23-04**

(52) **U.S. Cl.** **D23/372**

(58) **Field of Classification Search** ..... D23/372, D23/371; 126/299 R, 299 D

See application file for complete search history.

(57) **CLAIM**

I claim the ornamental design for a range hood, as shown and described.

DESCRIPTION

FIG. 1 is a top plan view of a range hood, showing my new design;

FIG. 2 is a bottom plan view thereof;

FIG. 3 is a front elevational view thereof;

FIG. 4 is a rear elevational view thereof;

FIG. 5 is a left side elevational view thereof, the right side being a mirror image of the right side;

FIG. 6 is a front perspective view of the range hood of my design; and,

FIG. 7 is rear perspective view of the range hood of my design.

1 Claim, 7 Drawing Sheets
